87 BY *C. P. Jaffel*
ATTORNEY

UNITED STATES PATENT OFFICE.

AUGUST WOLFF, OF NEW YORK, N. Y.

FRAME FOR SUPPORTING TRANSPARENT PLATES.

Application filed March 21, 1922. Serial No. 545,549.

To all whom it may concern:

Be it known that I, AUGUST WOLFF, a citizen of the United States, and resident of the borough of the Bronx, county of the Bronx, city and State of New York, have invented certain new and useful Improvements in Frames for Supporting Transparent Plates, of which the following is a specification.

10 This invention relates to improvements in frames for transparent plates enabling such a plate to be used as a baffle for preventing direct currents of air from striking the person or thing shielded or for other purposes.

15 Such shields are commonly used over the dasher or front of vehicles that travel at a high rate of speed, protecting the riders against the air currents caused by the velocity of the vehicle or otherwise and also

20 from the dust entrained in the air.

The principal object of the invention is to provide a shield or like device of non-fragile material and of such flexibility that it may be bent double if desired and to provide with 25 it a jointed or hinged frame whereby the device may be attached to or detached from an object and folded or extended at will.

These and other objects are attained by the novel construction and combination of parts 30 hereinafter described and shown in the accompanying drawings, forming a material part of this specification, and in which—

Figure 1 is a side elevation of a windshield made in accordance with the invention, one of the staying elements being shown in a released position;

Fig. 2 is a view of the same in end elevation;

Fig. 3 is a transverse sectional view taken 40 on line 3—3 of Fig. 1;

Fig. 4 is a fragmental sectional view taken through the shield frame on line 4—4 of Fig. 1;

Fig. 5 is a view similar to Fig. 2 but 45 showing the shield in a folded position;

Fig. 6 is a view indicating the invention as embodied in a cover for a container; and

Fig. 7 is a view of a modified form of frame.

50 The main element of the invention consists of a plate, or sheet 10 of transparent flexible and non-fragile material cut to suit the device with which it is intended to be used and held in a frame which may be composed

of angle irons 9, the longer sides 11 of which 55 are parallel with the plate 10 while the shorter sides 12 form a laterally projecting edge on the frame.

In the construction shown in Figs. 1 to 5 inclusive, a clamp strip 14 is also used, the 60 same being secured to the angle irons 9 by screws, rivets or pins 15, which pass through the plate 10, strip 14 and angle irons 9 and also preferably through cushioning elements 16, disposed upon either side of the plate 10 65 in such a manner as to form a tight joint between it and the strip 14 and dies 11 of the angle irons and to protect its edges. In the preferred form of the frame, shown in Fig. 7, the sides 11' of the angle irons are 70 provided with grooves which receive correspondingly shaped ribs or beads on the strips 14'.

The frame is preferably comprised of upper and lower sections joined by angular 75 out-turned side elements 18 and 20 respectively which are pivoted together by pins 19, these elements acting in the manner of a hinge.

The pivots 19 are fastened in the element 80 20 and may operate limitedly within the slots 21, formed in the elements 18. The slots 21 extend angularly at their inner sides as indicated at 22. Rotatably mounted on the pivots 19 are rollers 24, extending 85 past the inner edges of the frame and over which the plates 10 are bent when the shield is folded, as shown in Figure 4.

When it is desired to extend the shield, 90 levers 25 pivoted on pins 26 to the lower frame section and provided with operating handles 27 at their free ends, are turned upwardly, engaging with fixed clips 28, secured to the upper section of the frame in such a manner as to extend inwardly and to hold the levers in an upright position.

The sections of the frame are supported by the pivot pins 19 which are mounted in the upper ends of standards 34 secured to a suitable base 35 which may be the dash-board of an automobile.

Flexible strips 36 slotted as at 37 are arranged to bridge the space between the side elements 18 and 20 of the upper and lower sections of the frame. As shown, the ends of the strips 36 are secured at their ends over the clamping strips 14. The strips 36 reinforce the edges of the plate

10 between the side elements 18 and 20 and overlie the edges of the plate when the sections of the shield are folded as shown in Figure 4.

5 The nature of the material of the plate 10 is non-inflammable, as well as transparent, and is as readily flexed as a sheet of ordinary paper of corresponding thickness.

In the modification shown in Fig. 6, the 10 invention is embodied in a container, the same comprising side walls 65, having rigid end walls 66 and 67, respectively at the front and rear, the latter being of greater height than the front. Engaged centrally of the 15 side walls 65 are supporting brackets 68, having pivoted in their upper ends on the pins 69, the upturned elements 70 and 71 of the cover plates 72 and 73, the same corresponding to the elements 18 and 20 20 of the wind shield.

The cover 72 has engaged at its lower side an ear 74 which receives a pin 75, carried at the end of a segment rack 76, engaged with a pinion 79, fixed upon a short spindle 80 and adapted to be operatively engaged by a suitable lever handle (not shown). By this means, the pinion 79 may be turned, thus transmitting motion to the rack 76 and raising the cover plate 72 in an obvious manner.

The opposite cover plate 73 has attached to it an ear 84 in which is pivoted the upper end of a rack 85 meshing with a pinion 86 fixed on a spindle 87 actuated by a crank handle in a similar manner to the spindle 80. The racks 76 and 85 are arranged to move in guides 69 preferably provided with rollers (not shown) against which the rear edges of the racks 76 and 85 make contact.

40 Having thus described my invention what I claim as new and desire to secure by Letters Patents, is—

1. In a wind shield, the combination with a sectional frame, of a plate of flexible material engaged within said frame, a pair of hinges extended obliquely outward from the 45 shorter sides of said frame whereby the sec-

tions may be folded, and levers secured to said frame sides adapted to hold the frame rigidly when in an extended position. 50

2. In a wind shield, a rigid frame having an upper and lower section, a flexible transparent plate secured in said frame and extending between the sections thereof, cushioning elements interposed between said plate and said frame members, hinged elements secured to each of said sections, said hinge elements extending outward to one side of said frame, levers secured to one of said sections, and clips secured to the other of 55 said sections engageable by said lever whereby said frame may be held in an extended position.

3. In a wind shield, the combination with a frame, of a sheet of flexible material 65 mounted thereon, hinged joints combined with the shorter sides of said frame whereby said sheet may be folded, said frame comprising angle irons having their longer sides arranged for engagement with the surface 70 of the edge portions of the sheet, and being formed with longitudinally extending grooves, and means for securing the edge portions of the sheet to the frame comprising strips provided with ribs adapted to 75 fit over the sheet within the grooves of the angle irons.

4. A foldable wind shield comprising a fixed frame section, means for supporting said section in upright position, a movable 80 frame section hinged to said fixed frame section and adapted to swing downward in folded position parallel with said fixed frame section and upward into upright position in 85 alignment with said fixed frame section, a continuous flexible transparent plate secured to said frame section, means at the hinge of 90 said section for bending said plate, and means for locking said movable section in upright position.

In testimony that I claim the foregoing as my invention, I have signed my name hereunder.

AUGUST WOLFF.
